E. J. CASPER.
FOUNTAIN PEN.
APPLICATION FILED FEB. 9, 1920.

Patented Nov. 9, 1920.

FIG. 2.

FIG. 3.

FIG. 4.

FIG. 5.

Inventor
Edward J. Casper,
By his Attorneys
Edgar Dale Co.

UNITED STATES PATENT OFFICE.

EDWARD J. CASPER, OF NEW YORK, N. Y.

FOUNTAIN-PEN.

1,358,285.

Specification of Letters Patent.

Patented Nov. 9, 1920.

Application filed February 9, 1920. Serial No. 357,115.

To all whom it may concern:

Be it known that I, EDWARD J. CASPER, a citizen of the United States, and residing at New York, in the county of Kings and State 5 of New York, have invented certain new and useful Improvements in Fountain-Pens, of which the following is a specification, such as will enable those skilled in the art to which it appertains to make and use 10 the same.

This invention relates to fountain pens and particularly to devices of this class known in the art as self-filling fountain pens, and the object of the invention is to 15 provide improved means for operating devices of this class which will produce the desired result in a more efficient and economical manner by reason of the simplicity of the device and the method of constructing and assembling the same in connection with the body portion of the fountain pen.

The invention is fully disclosed in the following specification, of which the accompanying drawing forms a part, in which the 20 separate parts of my improvement are designated by suitable reference characters in each of the views, and in which:—

Figure 1 is a longitudinal sectional view through a fountain pen of the class under 25 consideration and showing my improvement in connection therewith;

Fig. 2 a view similar to Fig. 1 but showing only a part of the construction on an enlarged scale and with parts in a different 30 position;

Fig. 3 a partial section on the line 3—3 of Fig. 1 and on an enlarged scale;

Fig. 4 a partial section on the line 4—4 of Fig. 2;

Fig. 5 a view looking in the direction of the arrow 5 of Fig. 2; and,

Fig. 6 a view similar to Fig. 1 but showing only a part of the construction and indicating the method of mounting my improvement in connection with the body portion 45 of the fountain pen.

In the drawing I have shown at 10 the main tubular body portion of a fountain pen of the class under consideration. One 50 end of the body portion is closed as shown at 11 and the other end thereof is externally threaded as shown at 12 to receive a detachable cap 13. Detachably mounted within the body portion 10 is the usual supplemental body portion 14 which is connected 55 with and held in engagement with the main

body portion 10 in any desired manner. At one end of the supplemental body portion 14 is a pen point 15 and connected with the other end thereof is the usual flexible tube 60 16 composed of elastic rubber or other suitable material, and which constitutes the ink reservoir or container of the pen.

The above described construction is merely shown and described to illustrate a use of my invention and forms no part of this invention and, in practice, I connect 65 with the main body portion 10 a manually operated device 17 which operates in connection with the flexible tube 16 to discharge the ink from said tube or for refilling such tube. The device 17 consists of a metallic strip 18 mounted longitudinally of and within the tubular body 10 and to the inner end of which strip 18 is pivoted a link 75 19, which link 19 is also pivoted to another strip 20 as shown at 21. The outer end portion of the strip 18 extends through an aperture 22 in the closed end 11 of the body 10, and is bent into an approximately hook-shaped member 23. The part 24 of the hook-shaped member 23 extends in parallel lines with the strip 18 and the part 25 thereof extends transversely of the strip 18 and the part 24 and is slightly curved to correspond with the curvature on the outer face 80 of the end 11 of the body 10 as clearly shown in Figs. 1, 2 and 6 of the drawing.

The part 24 of the hook-shaped end portion 23 passes through another aperture 26 90 in the end 11 of the body 10, as is clearly shown in Figs. 1 and 2, while the transverse part 25 enters a recess 27 in the face of the end 11 thus producing a neat and finished appearance when the device is in its 95 normal position, as shown in Fig. 1. The recess 27 is enlarged at the opposite sides thereof, as shown at 28 in Fig. 5 of the drawing, to permit of the insertion of the nails of the fingers of an operator in withdrawing the device 17 into the position shown in Fig. 2.

One end portion of the strip 20 is slightly curved as shown at 29 and operates in connection with a concaved inner face 30 on the 105 head 11 of the body 10 to permit of the free action of said strip over said face in the use of the device. In attaching the device 17, or the separate parts thereof, to the body 10, the strip 18 is first fashioned into the form 110 shown in full lines in Fig. 6 and the outer or free end portion of the strip 18 is passed

through the aperture 22 with the strip 20 in the position shown in said figure after which the extended end portion of the strip 18 is bent into the hook-shaped member 23 as is indicated in dotted lines in said Fig. 6, and the strips 18 and 20 are then moved into the position shown in Fig. 1 and the supplemental body portion 14 with the flexible tube 16 connected therewith is passed into the main body portion 10 as is shown in said Fig. 1.

With the parts in the position shown in Fig. 1, and if it be desired to fill the flexible tube 16 with ink, the part 25 of the hook shaped member 23 is grasped by the operator and moved outwardly into the position shown in Fig. 2, in which operation the strip 20 is forced into the position shown in said Fig. 2 by the action of the link 19 on the strip 20, thus operated by the outward movement of the strip 18, and the flexible tube 16 will be fully compressed and all the air therein forced out through the supplemental body portion 14 in the usual manner, and by slowly returning the device 17 into its normal position as shown in Fig. 1, the expansion of the contracted flexible tube 16 will draw ink thereinto, if the pen point be placed in a fluid ink.

Of course, it will be understood that the fountain pen may be filled and refilled as many times as desired, and the ink removed from the flexible tube 16 for the purpose of cleaning the fountain pen, or for repairing the same, and it will also be seen that with my improved means for accomplishing the desired result little or no labor will be required in attaching the same to the body portion of the fountain pen, and by reason of the simplicity of the construction of the device, the desired result is produced in a very effective and efficient manner and at a nominal cost, and while I have shown certain details of construction for carrying my invention into effect, I am not necessarily limited to these details, and various changes in and modifications of the construction herein shown and described may be made, within the scope of the appended claims, without departing from the spirit of my invention or sacrificing its advantages.

Having fully described my invention, what I claim as new and desire to secure by Letters Patent, is:—

1. The combination with a fountain pen of the class described comprising a main body portion and a supplemental body portion detachably connected therewith and provided with a flexible tube mounted within the main body portion, of a self-filling attachment comprising a main part movable longitudinally of and within the main body portion, one end portion of said part projecting through the closed end of the body portion and provided with a hook-shaped

member which is normally countersunk in the closed end of the main body portion and by means of which said part is moved longitudinally of the main body portion, a supplemental part mounted within said body portion and movable transversely thereof, and a link connecting the supplemental body portion with the main body portion whereby the movement of said main part of the attachment will move said supplemental part to compress said flexible tube.

2. The combination with a fountain pen of the class described comprising a main body portion and a supplemental body portion detachably connected therewith and provided with a flexible tube mounted within the main body portion, of a self-filling attachment comprising a main part movable longitudinally of and within the main body portion and comprising a strip one end portion of which extends through and operates in the closed end of the main body portion, a supplemental part mounted within said body portion and movable transversely thereof, and a link pivoted to the supplemental part approximately centrally thereof and extending forwardly and pivoted to said main part whereby the movement of said main part longitudinally of the body portion will move said supplemental part transversely thereof.

3. The combination with a fountain pen of the class described comprising a main body portion and a supplemental body portion detachably connected therewith and provided with a flexible tube mounted within the main body portion of a self-filling attachment consisting of a main part movable longitudinally of and within the main body portion and comprising a strip one end portion of which extends through and operates in the closed end of the main body portion, a supplemental part mounted within said body portion and movable transversely thereof, and a link pivoted to the supplemental part approximately centrally thereof and extending forwardly and pivoted to said main part whereby the movement of said main part longitudinally of the body portion will move said supplemental part transversely thereof, said supplemental part operating in connection with said flexible tube within the main body portion.

4. The combination with a fountain pen of the class described comprising a main body portion and a supplemental body portion detachably connected therewith and provided with a flexible tube mounted within the main body portion of a self-filling attachment consisting of a main part movable longitudinally of and within the main body portion and comprising a strip one end portion of which extends through and operates in the closed end of the main body

portion, a supplemental part mounted within said body portion and movable transversely thereof, a link pivoted to the supplemental part approximately centrally thereof and extending forwardly and pivoted to said main part whereby the movement of said main part longitudinally of the body portion will move said supplemental part transversely thereof, said supplemental part operating in connection with said flexible tube within the main body portion, and that portion of the main part of the attachment which extends through the closed end of the fountain pen being fashioned to form a finger piece by which said main part may be operated.

5. A self filling attachment for fountain pens of the class described, comprising a main part adapted to move longitudinally of the body portion of the pen, a supplemental part adapted to move transversely of said body portion, a link member connected with the main and supplemental parts, the connection of said link member with said main part being forwardly of the connection thereof with the supplemental part, and means integral with said main part and passed through the closed end of the body portion for operating said main part and to move the supplemental part transversely.

6. A self-filling attachment for fountain pens of the class described, comprising a main part adapted to move longitudinally of the body portion of the pen, a supplemental part adapted to move transversely of said body portion, a link member connected with the main and supplemental parts, the connection of said link member with said main

part being forwardly of the connection thereof with the supplemental part, one end portion of the main part projecting through and operating in the closed end of said body portion, and a hook-shaped member on the projecting portion of said main part by means of which said main part may be moved longitudinally of the body portion to move the supplemental part transversely thereof.

7. A self-filling attachment for fountain pens of the class described comprising a main part adapted to move longitudinally of the body portion of the pen, a supplemental part adapted to move transversely of said body portion, a link member connected with the main and supplemental parts, the connection of said link member with said main part being forwardly of the connection thereof with the supplemental part, one end portion of the main part projecting through and operating in the closed end of said body portion, and a hook-shaped member on the projecting portion of said main part by means of which said main part may be moved longitudinally of the body portion to move the supplemental part transversely thereof, said hook-shaped member being normally counter-sunk in the closed end of said body portion.

In testimony that I claim the foregoing as my invention I have signed my name in presence of the subscribing witnesses this 31st day of January, 1920.

EDWARD J. CASPER.
